[57] CLAIM

The ornamental design for a liquid crystal video projector, as shown and described.

DESCRIPTION

FIG. 1 is a front, top and right side perspective view of a liquid crystal video projector, showing our new design, with the handle extended;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a cross-sectional view thereof, taken along line 8—8 in FIG. 2, with the internal system omitted; and,

FIG. 9 is a cross-sectional view thereof, taken along line 9—9 in FIG. 4, with the internal system omitted.
